ABSTRACT OF THE DISCLOSURE

Organic sulfoxides are manufactured by anodically oxidizing the corresponding organic sulfides in an aqueous organic solvent and electrolyte and by maintaining the anode potential between 0.4 and 1.7 volts.

This is a continuation of application Ser. No. 820,803, filed May 1, 1969, now abandoned.

The new process according to the present invention has been developed with a view to the electrolytic production of various organic sulfoxides, especially dialkyl or diaryl sulfoxides; it is particularly useful for the manufacture of dimethyl sulfoxide, an industrial product for which numerous practical applications have been found during the past decade.

The anodic oxidation of organic sulphides is a known operation and is capable of producing sulfoxides, as shown by Fichter and Braun in Berichte 47, 1526-34, and Pursley, in U.S. Pat. No. 3,200,054. Nevertheless, the operating procedures so far used led to results which industrially were of little interest. The sulfoxide, when obtained in an acceptable yield, necessitated a heavy expenditure for electricity, because the coulomb efficiency (Faraday yield) of the preparation was insufficient. On the other hand, the sulfoxide was generally obtained together with large proportions of other oxidized compounds, particularly the corresponding sulphone. Thus, for example, the first authors referred to above obtained diphenyl sulfoxide with a molar yield of 82.5% with respect to the diphenyl sulphide and with a coulomb efficiency of only about 62%. Pursley describes a process which gives mainly the sulphone, accompanied by a proportion of sulfoxide not exceeding 10%.

The present invention provides a truly industrial process by which it is possible to produce an organic sulfoxide, by anodic oxidation of the corresponding sulphide, with yields, both as regards weight and electrical, which are close or equal to 100%. In addition, the new process can be carried into effect easily and economically, as it does not require any electrolyte or costly solvent, and can be effected in conventional electrolyte cells, even without diaphragms; this last possibility provides the advantages of reducing the energy consumption. The new process offers perfect working safety, because of the absence of peroxidic products, in contrast with the chemical processes for the production of sulfoxides. Due to the fact that the oxidation selectivity results in practically only sulfoxide being produced, separation of the resultant product is considerably facilitated as compared with the known processes.

The invention results firstly from the discovery that it is not sufficient to regulate the temperature and the concentration of the electrolytic bath, as well as the current density and the voltage at the terminals of the cell, as has been done according to the prior art, for obtaining the best possible result. The applicants have found that an important factor which has to be taken into account is the anodic potential, which has to be kept within certain well-established limits in order that the sulfoxide is

2

formed alone and with a very high electrical yield. Other features of the invention which enable excellent results to be obtained are set out hereinafter in the present description.

In the process according to the invention, a solution of organic sulphide in an organic solvent containing water and a dissolved electrolyte is subjected to electrolysis between insoluble electrodes, the solvent and the anion of the electrolyte being selected from those of which the oxidation potential is decidedly higher than that of the sulphide, and the anode is maintained at a potential higher than that of the sulphide but lower than that of the solvent and of the anion.

Since generally the sulfoxides have oxidation potentials higher than the corresponding sulphides, it is expedient for the potential of the anode to be regulated, when carrying the new process into effect, to a value lower than that which corresponds to the oxidation of the formed sulfoxide; in this way, the production of more oxidized compounds, particularly sulphone, is avoided.

Although the oxidation potentials can vary with the nature of the treated sulphides, they are generally of the order of +0.4 to 1.7 volts on carbon or platinum anodes. In general, the preferred range of anodic potential according to the invention is approximately +0.5 to +1.6 volts. It is obvious that the potential to be applied has to be re-adjusted according to the nature of the anode being used. For example, in the case where dimethyl sulphide is oxidized into dimethyl sulfoxide with carbon or platinum anodes, the anode potential is usually from about +0.8 to +1.1 in dimethyl formamide and can reach +1.6 in acetonitrile. The potentials which are indicated in the present specification are understood to be by comparison with the saturated calomel electrode.

The anodic oxidation according to the invention can be represented by the summary reaction:

in which the hydrocarbon groups R^1 and R^2 are like or different and can be such as alkyl, aryl, cycloalkyl alkaryl, aralkyl, optionally substituted with other groups, such as, for example, halogen, hydroxyl and carboxyl groups. Thus, for example, each of the groups R^1 and R^2 can be a methyl, ethyl, propyl, isopropyl, n-butyl, iso-butyl, tert-butyl, hexyl, decyl, dodecyl, eicosyl, etc. group, or phenyl, tolyl, cresyl, ethyl-phenyl, dodecylphenyl, chlorophenyl, cyclohexyl, cyclopentyl, naphthyl or other group.

As previously indicated, the solvent, which plays an important part, is selected from the liquids of which the oxidation potential, under the indicated working conditions, is decidedly higher than that of the treated organic sulphide. This solvent must obviously be capable of dissolving an appreciable quantity of an electrolyte; on the other hand, with a certain proportion of water added thereto, it must show a dielectric constant sufficient to lead to the necessary ionic dissociation of the electrolyte. Bearing these conditions in mind, it is easy to find various appropriate solvents, among which can be mentioned, for example, the dialkyl formamides and particularly dimethyl formamide, acetonitrile, nitromethane, etc.

According to one preferred feature of the invention, the solvent is itself a sulfoxide and best of all, actually the sulfoxide which is to be manufactured. By way of example, dimethyl sulfoxide constitutes an excellent solvent which is applicable for the manufacture of various dialkyl or diaryl sulfoxides, and more especially, the manufacture of dimethyl sulfoxide.

Suitable as electrolyte are the different mineral salts, such as halides, halogenates, perhalogenates, sulphates, nitrates, sulphonates, or others, of the alkali and/or alkaline earth metals, of which the anion is oxidized at

a potential decidedly higher than the oxidation potential of the treated organic sulphide; the acids in which the anion also satisfies this condition are likewise suitable. It is understood that the choice of the suitable electrolyte depends on the nature of the sulphide which is to be oxidized.

For carrying the new process into effect, the anode of the electrolytic cell can be platinum, gold, nickel, palladium, cobalt, rhodium, iridium, tantalum, carbon, or other materials which cannot be attacked under the working conditions. Alloys of the various aforementioned metals can be used. Carbon, preferably in the form of graphite, can with advantage be impregnated in accordance with the conventional electro-chemical technique. The anode can also be formed of lead dioxide.

As the nature of the cathode is of less importance than that of the anode, metals such as iron, stainless steel, lead, mercury, copper, etc. are suitable, in addition to the materials indicated above for the anode, with the exception of lead dioxide. Obviously, since the cathode must remain insoluble, the choice thereof depends on the nature of the electrolyte being used.

When the electrolytic cell is arranged for working without a diaphragm, it is necessary to choose a cathode on which the sulphoxide is not reduced.

The concentration of organic sulphide in the liquid medium to be electrolyzed can vary considerably; with sulphides such as dimethyl sulphide, it is advantageous to work in relatively concentrated solutions, for example, with a content by weight of 5 to 50% or better still, from 10 to 40%.

It is generally preferable for the molar ratio between the water which is present and the sulphide initially introduced to be equal to or higher than 0.45, and particularly from 0.45 to 20.

The process according to the invention is preferably carried out at moderate temperatures, especially between 0 and 100° C. For relatively volatile sulphides, it is expedient to operate, for example, between 10° and 35° C.; excellent results are obtained with dimethyl sulphide at ambient temperature, that is to say, between approximately 20° and 30° C. In the case of heavier sulphides, as, for example diphenyl sulphide, it is advantageous to raise the temperature for increasing the conductivity of the medium.

After the anodic oxidation of the sulphide, the sulphoxide is separated from the liquid medium by any known means, for example, by distillation and/or crystallization, etc.

In the particular case of dimethyl sulphoxide $(\text{CH}_3)_2\text{SO}$, which industrially is very important, one extremely advantageous form of the new process consists in carrying out the oxidation of the dimethyl sulphide in solution in dimethyl sulphoxide.

Although the metals referred to above are quite suitable in the case of dimethyl sulphoxide, platinum and carbon are particularly advantageous when the electrolyte is acid; acids such as sulphuric, perchloric, nitric or toluosulphonic acids are very suitable.

As regards the cathode, in the particular case referred to above, it advantageously is platinum or stainless steel, which can be used without a diaphragm. However, graphite can only be suitable for forming the cathode if a diaphragm is, employed; moreover, the catholyte must not contain dimethyl sulphoxide, because this latter would be reduced on contact with carbon. With conventional cathodes of mercury, lead, copper, etc., the same precautions have to be taken as with carbon.

The preferred arrangement for employing the new process for the manufacture of dimethyl sulphoxide is a cell without a diaphragm, having one or more graphite anodes and one or more stainless steel or platinum cathodes. The cell has an agitation system and a cooling arrangement which permits the temperature of the electrolytic medium to be kept below 37.3° C., which

represents the boiling point of dimethyl sulphide. A device is preferably associated with the cell for recovering the sulphide entrained by the hydrogen liberated at the cathode. This device comprises one or more known means, such as condensers or adsorption or absorption columns. According to a preferred feature of this invention, the recovery device is formed by a dimethyl sulphoxide washer; the sulphide dissolved by this device can be directly re-introduced, with its solvent, into the electrolysis cell.

The electrolysis can be continued until complete exhaustion of the sulphide initially introduced with the electrolytic liquid. However, in order to avoid a considerable drop in intensity, it may be advantageous to interrupt the electrolysis when only a part of the sulphide is oxidized, to separate the products and to recycle the remaining sulphide in the electrolytic cell. It is also possible periodically to extract a portion of the electrolyzed liquid, in order to separate therefrom the sulphoxide which has formed and to replace it with fresh sulphide, before all the initial sulphide is oxidized.

The separation of the products of the electrolytic mixture can be effected by any known means, with or without neutralization of the electrolyte.

All or certain of these operations can be effected continuously.

The non-limiting examples which follow illustrate the invention, by reference to the accompanying drawings.

FIG. 1 is a vertical axial section of the electrolysis cell which is used, along the line I—I of FIG. 2.

FIG. 2 is a top plan view of the same cell.

EXAMPLE 1

The preparation of dimethyl sulphoxide is effected by electrolysis of a solution composed of:

35 17 g. of dimethyl sulphide
100 g. of water
46 g. of sodium paratoluosulphonate
900 ml. of dimethyl formamide.

40 The operation is carried out in a cylindrical cell 1 (see FIGS. 1 and 2) with a capacity of about 160 ml. Three anodes A1—A2—A3, formed by small graphite plates or grids of platinum wire, are disposed in the form of a U at the centre of the cell and electrically connected together.

45 The cathodes C1 and C2 are grids of stainless steel or platinum wire; the first cathode C1, in the form of a U, is placed inside the U formed by the anodes A1—A2—A3, while the second is an arc of a circle concentric with the walls of the cell 1. The two cathodes are connected to one another. The circular cathode C2 encloses the anode branches A1 and A3, but not the transverse branch A2, behind which is disposed the reference electrode 4 for measuring the anode potential. The agitation is assured by a magnetic agitator 5. The water bath optionally provided for cooling the cell is not shown. The total surface of the anodes A1, A2 and A3 is 64 cm.², and that of the cathodes C1 and C2 together is 75 cm.².

50 The anode potential is measured in known manner in relation to the saturated calomel electrode 4. The contact with the solution of the cell is assured by a bridge containing a saturated solution of KNO_3 in the same solvent as that of the electrolyzed medium, especially dimethyl formamide or dimethyl sulphide. The end of the bridge is formed by a Luggin capillary 6 coming into contact with the anode A2.

55 The anode potential of the lateral branches A1 and A3, which is generally slightly stronger than on A2, because of the asymmetry of the cell, is determined in the same manner.

60 A direct current is caused to flow, the anode potential being +0.89 volt on A2 and +1.04 volts for A1 and A3. The current density is 0.43 A./dm.². The temperature of the solution is from 20° to 25° C. When 42.5% of the theoretical quantity of electricity has passed through the solution, the electrolysis is stopped and the coulomb yield

of the formed dimethyl sulphoxide is determined, after having measured the sulfoxide by chromatography: this electric yield is 100%.

EXAMPLE 2

Using the same cell as in Example 1, a solution of the same composition, but in which the electrolyte is sulphuric acid having a concentration of 0.28 N, is electrolyzed.

The anode potential is +0.91 v. for A2 and +1.09 v. on A1 and A3; the anode current density is 0.48 A./dm.²; the temperature is kept between 20° and 25° C. After the passage of 80% of the theoretical current, the coulomb yield of the formation of dimethyl sulfoxide is found to be 100%.

EXAMPLE 3

In a cell without a diaphragm, equipped with an anode consisting of a platinum grid and a stainless steel cathode, a solution having the following composition is electrolyzed:

Solvent	Dimethyl sulphoxide.
Dimethyl sulphide	215 g. per l. of solution.
Water	100 g. per l. of solution.
H ₂ SO ₄	43.5 g. per l. of solution.

The anode potential is: +0.84 v. at A2 and +0.995 v. at A1 and A3, the temperature being kept at 22°-27° C. The voltage at the terminals of the cell varies between 3.5 and 4.5 v. and the current between 0.3 and 0.4 A.; the current density is 1.9 A./dm.².

After passage of 40.5% of the theoretical current, the coulomb yield of dimethyl sulfoxide produced is 95.5%.

EXAMPLE 4

A solution having the same composition as in Example 3 is electrolyzed in a similar cell, in which the platinum anode is replaced by a carbon anode. The anode potential is +0.88 v. for A2 and +1.03 v. for A1 and A3; the temperature is kept at 23°-27° C. The voltage at the terminals of the cell varies between 7 and 10 volts and the current between 1.5 and 2.1 A.; the current density reaches 3.3 A./dm.². After passage of 41.5% of the theoretical current, a coulomb yield of 95% of dimethyl sulfoxide is obtained.

EXAMPLE 5

Using the same cell and the same conditions as regards anode potential and temperature as in Example 4, a solution with the following composition is electrolyzed:

Solvent	Dimethyl sulphoxide.
Dimethyl sulphide	340 g. per litre of solution.
H ₂ O	45 g. per litre of solution.
H ₂ SO ₄	43.5 g. per litre of solution.

The anode potential on A2 is +0.88 v. and on A1 and A3 is +1.035 v. The voltage at the terminals varies from 8 to 8.5 v. and the current from 0.8 to 0.9 A., and hence the mean current density is 1.33 A./dm.². After passage of 45.4% of the theoretical current, the coulomb yield is found to be 96.2% of DMSO.

EXAMPLE 6

Using a cell without a diaphragm and equipped with carbon anodes and platinum cathodes, a solution of the following composition is electrolyzed:

Solvent	Dimethyl formamide.
Diethyl sulphide	126 g. per litre of solution.
H ₂ O	50 g. per litre of solution.
H ₂ SO ₄	43.5 g. per litre of solution.

The temperature is kept between 20° and 28° C. and the anode potential is kept at a value from +0.835 to +0.98 v., relative to the saturated calomel electrode. Under these conditions, the potential difference at the terminals of the cell varies from 3 to 5 v. and the cur-

rent strength from 0.25 to 0.50 A. (mean current density 0.6 A./dm.²). After passage of 50.5% of the theoretical current, a coulomb yield of 97.5% of diethyl sulphoxide is obtained.

EXAMPLE 7

Using the same cell as in Example 6, a solution having the following composition is electrolyzed:

Solvent	Dimethyl formamide.
Diphenyl sulphide	140 g. per litre of solution.
H ₂ O	50 g. per litre of solution.
H ₂ SO ₄	43.5 g. per litre of solution.

The anode potential is from +0.835 to +0.965 v. relative to the saturated calomel electrode. The temperature is kept between 22° and 27° C. The potential difference at the terminals varies between 2.2 and 3.5 v. and the current strength between 0.1 and 0.2 A., the mean anode current density being 0.25 A./dm.².

After passage of 61% of the theoretical current, the coulomb yield of diphenyl sulfoxide is raised to 94%.

The examples illustrate the anodic oxidation under atmospheric pressure, but it is possible to work under a higher pressure, in which case, the temperature can be higher than that at which the treated sulphide boils.

We claim:

1. A process for the manufacture of an organic sulfoxide consisting essentially of anodically oxidizing the corresponding organic sulfide of the formula R¹-S-R² wherein R¹ and R² are individually selected from the group consisting of unsubstituted and halogen-, hydroxy- and carboxy-substituted alkyl, aryl, cycloalkyl, alkaryl and aralkyl groups in an aqueous organic solvent selected from the group consisting of dialkyl formamide, aliphatic nitrile, nitroalkane and organic sulfoxide, and an electrolyte selected from the group consisting of an acid, and a halide, halogenate, perhalogenate, sulfate, nitrate or sulfonate of an alkali metal or alkaline earth metal between insoluble electrodes at a temperature between 0° and 100° C., wherein said anode is carbon or platinum and the anode potential between 0.4 and 1.7 volts.

2. Process according to claim 1 wherein the sulfide is dimethyl sulfide.

3. A process for the manufacture of an organic sulfoxide which comprises anodically oxidizing the corresponding organic sulfide in an aqueous organic solvent selected from the group consisting of dialkylformamide, aliphatic nitrile, nitroalkane and organic sulfoxide, and an electrolyte selected from the group consisting of an acid, and a halide, halogenate, perhalogenate, sulfate, nitrate or sulfonate of an alkali metal or alkaline earth metal between insoluble electrodes at a temperature between 0° and 100° C., wherein the anode is carbon or platinum and the anode potential is between 0.4 and 1.7 volts.

4. Process according to claim 3 wherein the electrolysis is interrupted when 40% to 80% of sulfide has been oxidized, the organic sulfoxide product is separated from the electrolyzed mixture and the remaining unoxidized sulfide is subjected to additional anodic oxidation.

5. Process according to claim 3 wherein the anode potential is between 0.5 and 1.6 volts.

6. Process according to claim 3 wherein the anode potential is about 0.8 to 1.1 volts.

7. Process according to claim 3 wherein the temperature is between 10° and 35° C.

8. Process according to claim 3 wherein the sulfide is dimethyl sulfide, the temperature is between 10° and 35° C., and wherein the anode potential is about 0.8 to 1.1.

9. Process according to claim 3 wherein the organic sulfide to be oxidized is of the formula R¹-S-R² wherein R¹ and R² are individually selected from the group consisting of unsubstituted and halogen-, hydroxy- and

carboxy-substituted alkyl, aryl, cycloalkyl, alkaryl and aralkyl groups.

10. Process according to claim 9 wherein the sulfide is dimethyl sulfide.

11. Process according to claim 3 wherein the mixture to be electrolyzed contains 5% to 50% by weight of dimethyl sulfide.

12. Process according to claim 11 wherein the molar ratio between the water and the sulfide present in the mixture is equal to or higher than 0.45.

13. Process according to claim 12 wherein the said ratio is from 0.45 to 20.
